MACHINE FOR USE IN MANUFACTURING SHOES

Harry Hallam, Leicester, England, assignor to
United Shoe Machinery Corporation, Paterson,
N. J., a corporation of New Jersey

Application April 21, 1932, Serial No. 606,691
In Great Britain May 20, 1931

5 Claims. (Cl. 51—239)

This invention relates to machines for use in manufacturing shoes and is herein disclosed as embodied in a machine for grinding, to a desired bevel, the heel ends of insoles.

5 Light weight insoles are at present commonly incorporated in women's shoes and, particularly when the shoes are to be fitted with Louis heels, it is usual to reinforce such insoles at their heel ends and often for a short distance along the 10 waist in order to stiffen the heel end of the shoe. The reinforcing material most frequently used for this purpose is a hard stiff fibre which offers a considerable resistance to cutting or trimming.

15 It is desirable, in order that the shape of the shoe at the heel end may present a smooth continuous curve from the upper edge of the shoe at the heel end to its heel seat portion, to bevel the marginal portion around the lower edge of the insole at such an angle that the curve of the back 20 of the last and the contour of the edge of the insole are more or less continuous. Ordinary leather insoles are usually trimmed to a desired bevel by a rotary cutting tool. In the case of a reinforced insole the beveling operation often takes 25 place principally upon the layer of reinforcing material, since the latter is secured to that side of the insole which is further from the last bottom and may be of material thicker than that of the remainder of the insole. When the reinforcing 30 material is relatively stiff and hard as compared with leather, as is usually the case, it is found that trimming cutters which are capable of operating effectively upon un-reinforced leather insoles sometimes require to be resharpened 35 with objectionable frequency.

It is, accordingly, an object of the present invention to avoid this difficulty. As herein disclosed this is done by the provision of an improved abrading machine well adapted to use for 40 grinding the edges of sheet material such as soles and like articles to the desired beveled form.

In accordance with a feature of the invention, a work guide, which extends substantially parallel to the axis of a rotary abrading tool, is provided for engaging a face of a piece of sheet material for determining the angular relation of the material to the operating surface of the abrading tool and a gage is positioned between the work guide and the operating surface of the tool for 45 engaging an edge portion of the sheet material for limiting the movement of the material toward the abrading tool thereby to limit the amount of material which can be removed from the edge. In the 50 illustrated machine the abrading tool is in the form of a wheel having a peripheral grind-

ing surface, and supporting means is provided for the work guide constructed and arranged for adjustment to vary the angular relation between the article to be abraded and the operating surface of the grinding wheel. The edge engaging member for limiting the amount of material which can be abraded from the work piece consists of a thin blade-like member extending toward the abrading tool and terminating in an edge which is closely adjacent to the operating 10 surface of the abrading tool.

These and other features of the invention will be described as embodied in an illustrated machine and pointed out in the appended claims.

Referring now to the accompanying drawing, 15 Fig. 1 is a view in front elevation showing the head of the machine; and

Fig. 2 is a view in side elevation of the parts seen in Fig. 1 looking from the left.

The frame of the illustrated machine comprises 20 a vertical column 1 having a head casting 3 at its upper end in which is supported a horizontal shaft 5 extending from left to right of the operator as he stands in front of the machine. The horizontal shaft is provided with fixed and idler pulleys 2 and 4 respectively, and a belt 6 driven from any suitable source of power may be shifted from the idler pulley 4 to the fixed pulley 2 to start the machine. The shaft 5 is driven by the belt 6 in a counterclockwise direction as viewed 25 in Fig. 2 and at a high speed preferably in the neighborhood of two thousand five hundred revolutions per minute. A grinding wheel 7 is secured to the left hand end of the shaft to be rotated thereby and is preferably about 7" in diameter by 30 3/4" wide. This grinding wheel is preferably of relatively soft composition and may conveniently be a wheel manufactured by the Waltham Grinding Wheel Company of America having a softness identified by that company as of the grade 46H. The wheel 7, regarded as a trimming tool, will have a path of action which coincides with its 35 operating surface, i. e. its periphery. A bracket 9 is secured to the machine head and extends close to the grinding wheel 7 and has bolted to it a circular dust collecting hood 11 enclosing the wheel 7. The hood 11 has an outlet opening in its rear portion, from which outlet opening a suction conduit 87 extends downwardly. The suction conduit 87 is connected to the usual exhaust blower (not shown) for disposing of dust which arises from the operation of the wheel 7 upon the work.

A short stationary sleeve 13 surrounding the 40 shaft 5 is located between the right hand side of 45

the dust collecting hood 11 and the left hand end of the head 3 of the machine and is rigidly secured to the latter by a collar 15 which is screwed to the head. A short bracket 17 is adjustably clamped on the sleeve 13 close to the dust collecting hood 11 and extends upwardly and forwardly from the sleeve. This bracket 17 has a guide rib 19 formed on it which extends forwardly and rearwardly of the operator and is inclined slightly downwards towards him. A carrier member 21 is mounted for adjustment along this guide rib and has a slot 23 formed in it through which passes a clamping bolt 25 engaging a threaded hole in the bracket 17. The bracket 15 also has a threaded hole 27 formed through it parallel to the said guide rib and just below it. A threaded stem 29 having a hand wheel 31 at its rear end passes through the threaded hole 27 and carries collars 33 spaced apart near its front end which are secured to the threaded stem and receive between them a downwardly extending lug 35 formed upon the carrier member 21 just rearward of its forward end. The forward end of the carrier member has an arcuate guideway 37 formed in its left hand face in which is secured a block 39 carrying a pair of work engaging members. The block 39 may be clamped in any desired position of adjustment along the arcuate guideway 37 by a clamping bolt 40. The said block 39 has a depending curved member 41 secured to it which member is bifurcated to straddle the grinding wheel and is curved downwardly and forwardly at its lower end. To the extreme forward end of this portion is secured a work-supporting table 43 which is mounted on a horizontal pivot 45 extending parallel to the shaft 5 of the machine. This work table is relatively small being about $1\frac{1}{2}$ " in length and in breadth and is urged in a forward and upward direction by a spring 47 which is located in a housing in the curved member 41 and bears against the underside of the table, faces on the forward end of the curved member 41 and on a portion of the table surrounding the pivot 45 limiting the upward movement of the table. The depending member 41 is arranged to be adjusted bodily forwardly and rearwardly of the machine by means herein-after described until the rear edge of the work table 43 lies close to the edge of the grinding wheel 7. The curved depending member 41 has a guideway 49 formed in it which is located above the work supporting table 43 and extends downwardly and rearwardly at right angles to the general plane of the latter. A work positioning foot 51 (about half an inch wide) is located with freedom for adjustment in the said guide and has a plain underface which is arranged to lie parallel to the axis of the wheel 7 and to the general plane of the work table 43 when the latter is depressed somewhat against the action of the spring 47 and is spaced therefrom a distance more or less equal to the thickness of an insole. An edge gauge comprising a blade-like member 53 is secured by a clamping bolt 54 to the rear face of the work positioning foot 51 and is adjustable upwardly and downwardly along it so that the lower end of the blade-like member projects a small extent (preferably $\frac{1}{2}$ " or thereabouts) beyond the lower face of the work positioning member and lies almost in contact with the periphery of the grinding wheel. The lower end of this blade-like member is reduced in thickness to a knife edge so that an insole which is pressed rearwardly against the forward side of the blade-like member can be so brought against the grinding wheel that the

whole thickness of the insole (excluding that small portion shielded by the projecting portion of the blade-like member) will be operated upon by the grinding wheel.

The work table 43 and positioning foot 51 are so located vertically of the wheel that an insole supported on the side which is not reinforced by the work table and engaged on its upper reinforced side by the foot will be presented to the periphery of the grinding wheel about $1\frac{1}{2}$ " below the axis of the grinding wheel. When the table lies at an angle of about 45° to the horizontal with the insole positioned between the table and the foot the insole will lie in a plane which is tilted downwardly about twenty-two degrees from a radial line drawn to the edge of the grinding wheel near the lower end of the blade-like member 53, and the action of the grinding wheel on the insole will produce on the edge of the latter a bevel extending at about 22° to a line drawn perpendicularly to the reinforced face of the insole the said bevel extending from the lower face of the insole almost, but not quite, to its upper face. By adjusting the block 39 aforesaid along the curved guideway 37 the angle at which the work table lies relatively to the horizontal can be varied. This curved guideway is concentric about the lower end of the blade-like member 53 when the latter projects about $\frac{1}{2}$ " below the lower face of the work positioning foot, so that movement of the block along the guideway will not disturb the closeness of the foot to the periphery of the grinding wheel. The angle through which the curved guideway 37 extends is such that by moving the block along the curved guideway the angle of bevel produced on the insole may be varied between limits of 11° to a line drawn perpendicularly to the reinforced face of the insole and 31° to that line.

As the grinding wheel 7 wears away the work table 43 the foot 51 may be kept close up against the periphery of the latter by rotating the threaded stem 29 aforesaid to cause the work table and the work positioning foot to move bodily towards the grinding wheel along a path parallel to the axis of the threaded stem 29.

In the normal operation of the machine, the operator stands in front of the machine as seen in Fig. 1 and inserts a reinforced insole I with the reinforced side R downwards, between the spring-supported work supporting table 43 and the work positioning foot 51 which will thereupon cooperate to grip the insole lightly between them. The operator then moves the insole between the table and the work-engaging foot so that the toward end of the reinforcing material at one side of the waist of the insole is opposite the periphery of the grinding wheel. He then pushes the insole rearwardly towards the periphery of the wheel until the insole contacts with the lower end of the blade-like member 53. The grinding wheel will then commence to bevel off the lower edge of the insole and reinforcing layer at the desired angle and the operator then gradually moves the insole endwise along between the work table and positioning foot, while still urging the insole against the wheel, to cause the beveling operation to proceed towards the heel end of the insole. When he reaches the heel end, he swings the insole gradually around through about one hundred and eighty degrees while still maintaining the insole pressed against the wheel, thus causing the beveling operation to be carried out around the heel end of the insole. After the beveling operation has been effected around the heel

end, the operator moves the insole lengthwise once more in the opposite direction to that in which he previously moved it and thus causes the beveling operation to be continued along the remaining 5 side of the insole until it has completely bevelled the reinforced portion of the insole.

In order to prevent the surface of the grinding wheel from becoming glazed by its grinding action on insoles a dressing wheel 55 is provided 10 which can be lowered into contact with the periphery of the wheel and serves by pressing on the latter to keep its surface rough. This dressing wheel 55 comprises a number of corrugated steel discs mounted side by side on a pin 57 which is 15 secured in the rear end of a rocker arm 59 which is housed inside the dust hood 11 and is secured at its forward end to a freely rotatable shaft or pivot 61 which extends through the left hand side of the dust hood surrounding the wheel. A 20 spring 63 is secured at one end to the arm 59 which carries the dressing wheel and at the other end to a hook on the dust hood and tends to pull the dressing wheel down on to the periphery of the grinding wheel. A hand lever 65 is freely 25 mounted on the pivot 61 for the arm 59 on the outside of the dust hood and has a pin 67 secured to it close to the pivot which pin extends towards the left. A cap member 69 is secured to the extreme left hand end of the pivot 61 and 30 has an arcuate slot 71 formed in it into which slot extends the pin 67 secured to the hand lever 65. A spring 73, which is stronger than the spring 63 which is connected to the arm 59 carrying the dressing wheel, is secured to the hand lever 65 and tends to pull the latter rearwardly so that the pin 67 secured to the hand lever presses against the rearward end of the slot 71 formed in the 35 cap member 69 and thus lifts the link 59 carrying the dressing wheel away from the grinding 40 wheel. By pulling the hand lever 65 forwardly against the action of the spring 73 the pin 67 can be retracted from the rearward end of the slot 71, thereby enabling the spring 73 to press the dressing tool against the grinding wheel. It will 45 be noted that the pressure of the dressing tool against the grinding wheel is not derived from the lever 65 but from the spring 63, and is accordingly predetermined. If, however, a greater pressure is desired, the operator can pull the 50 lever 65 forwardly far enough to cause the pin 67 to bear against the forward end of the slot 71, thus transmitting additional pressure to the dressing tool. Immediately the hand lever 65 is released the dressing wheel is raised owing to the 55 rearward movement of the hand lever under the action of the spring 73 which is connected to it.

In order to allow of free access to the grinding wheel the left hand side of the dust hood which carries the pivot 61 for the link 59 is formed as 60 a door 77 which is secured to the dust hood on a vertical pivot pin 79 near to its rear side. A thumb screw 81 normally holds the door 77 clamped in closed position but by release of the thumb screw the door can be swung open and the grinding 65 wheel can be easily seen and reached. Furthermore when the door is open the dressing tool and its associated mechanism are also accessible.

The above-described dressing tool, together with its operating mechanism, is not claimed 70 herein, but constitutes the subject-matter of my copending application Serial No. 728,146, filed May 29, 1934, which is a division of the present application.

In order to prevent excessive accumulation of 75 leather dust in the bottom of the dust hood from

fouling the grinding wheel a pocket 82 having an opening 83 is formed in the dust hood below the axis of the grinding wheel which opening is connected by a pipe 85 to the air exhausting duct 87 which communicates with the hood 11 itself. 5 A butterfly valve 89 is located in the pipe 85 just below the bottom of the dust hood and, under the influence of a spring 91, normally closes the pipe and forms a wall against which the leather dust can accumulate. The operator can however 10 when he so desires open the butterfly valve and allow the air suction to draw away the leather dust.

By adjusting the bracket 17 around the sleeve 13 the work supporting table and work positioning foot can be raised or lowered around the periphery of the wheel to give the most convenient 15 working position for the operator.

Having thus described my invention, what I claim as new and desire to secure by Letters Pat- 20 ent of the United States is:

1. A machine for beveling the edges of soles and like articles comprising an abrading tool having a peripheral operating surface, a work guide engageable with a face of a sole for determining the angular relation of the sole with respect to the periphery of said abrading tool, means for limiting the approach of the sole toward the periphery of said tool thereby to limit the amount of material which can be abraded 30 from the edge of the sole, and supporting means for said work guide constructed and arranged for adjustment to vary the angular relation between the sole and the operating surface of said abrading tool while maintaining substantially 35 constant the relation between said approach-limiting means and said abrading tool.

2. A machine for abrading the edges of soles and like articles comprising a rotary abrading tool, a work guide having an operating surface substantially parallel to the axis of said abrading tool and extending close to the operating surface of said abrading tool and engageable with a face of a sole for positioning the sole in a desired 40 relation to the operating surface of said tool, and a gage positioned between said work guide and the operating surface of said tool for engaging a portion of the edge of the sole to limit the amount of material which can be abraded from the sole. 45

3. A machine for abrading the edges of soles and like articles comprising a rotary abrading tool, a work guide having an operating surface substantially parallel to the axis of said abrading tool and extending close to the operating surface of said abrading tool and engageable with a face of a sole for positioning the sole in a desired 50 relation to the operating surface of said tool, and a gage in the form of a thin blade-like member positioned between said work guide and the operating surface of said tool for engaging a portion of the edge of the sole to limit the amount of material which can be abraded from the sole, said gage extending toward the abrading tool and terminating in an edge which is closely adjacent to the operating surface of the abrading tool. 55

4. A machine for abrading the edges of soles and like articles comprising an abrading tool, a work guide engageable with a face of a sole to be abraded for determining the angular position of the sole with respect to the operating surface of said abrading tool, a gage extending toward the abrading tool and engageable with a portion of the edge of the sole to limit the amount of material which can be abraded from the sole, 60
